United States Patent Office

Des. 191,037
Patented Aug. 8, 1961

191,037

CHILD'S CART OR THE LIKE

Joseph A. Mayberry, Goshen, Ind., assignor to Goshen
Manufacturing Company, Goshen, Ind., a corporation of Indiana

Filed Dec. 1, 1960, Ser. No. 63,066

Term of patent 14 years

(Cl. D14—3)

FIG. 1 is a front perspective view of a child's cart or the like showing my design;

FIG. 2 is a side elevational view thereof, and

FIG. 3 is a rear elevational view thereof.

I claim:

The ornamental design for a child's cart or the like, as shown.
